UNITED STATES PATENT OFFICE.

DOMENICO T. CASALE, OF WILLIAMSPORT, PENNSYLVANIA.

NUT-LOCK.

1,129,955.

Specification of Letters Patent.

Patented Mar. 2, 1915.

Application filed November 18, 1914. Serial No. 872,785.

To all whom it may concern:

Be it known that I, DOMENICO T. CASALE, a subject of the King of Italy, residing at Williamsport, in the county of Lycoming and State of Pennsylvania, have invented certain new and useful Improvements in Nut-Locks, of which the following is a specification, reference being had to the accompanying drawings.

- 10 This invention relates to certain improvements in nut locks and has relation more particularly to a device of this general character wherein are employed superimposed reversely threaded nuts; and the object of 15 the invention is to provide a device of this general character having novel and improved means coacting with the superimposed nuts whereby the same are effectively maintained against relative movement.
- 20 The invention consists in the details of construction and in the combination and arrangement of the several parts of my improved nut lock whereby certain important advantages are attained and the device is 25 rendered simpler, less expensive and otherwise more convenient and advantageous for use, all as will be hereinafter more fully set forth.

The novel features of the invention will 30 be carefully defined in the appended claim.

In order that my invention may be the better understood, I will now proceed to describe the same with reference to the accompanying drawings, wherein—

35 Figure 1 is an elevational view of a bolt having applied thereto a nut lock constructed in accordance with an embodiment of my invention; Fig. 2 is a fragmentary view, partly in elevation and partly in section, 40 illustrating in detail certain features of the invention; Fig. 3 is a transverse sectional view through one of the nuts herein embodied; and Fig. 4 is a perspective view, detached, of the locking key herein employed.

As disclosed in the accompanying drawings, B denotes a bolt of conventional form having its free extremity provided with the reversely threaded portions 1 and 2 with 50 which are adapted to coat the burs or nuts 3 and 4, respectively, for a purpose and in a manner which is believed to be self-evident.

Each of the side faces of the nut or bur 3 is provided at substantially its center with 55 a socket 5, the side walls whereof being concaved, as indicated at 6, and in communica-

tion with such socket is the open ended slot 7 disposed outwardly and longitudinally of the bolt B when the bur is in applied position. The nut or bur 4 is also provided at 60 the center of each of its side faces with a socket 8 of similar formation as the socket 5, hereinbefore referred to, and said socket is intersected by the groove or slot 9 disposed transversely of and entirely across the 65 side face.

When in operative position, the slots or grooves 9 are adapted to register or align with the slots 7 in order to receive the key 10 formed of wire or the like and of suitable gage. Fixedly secured to one extremity of the key 10 is a head or clench 11 formed, preferably, of soft metal, although I do not wish to be understood as limiting myself in this particular respect. This 70 clench or head 11 is adapted to be inserted within a socket 5 and upon being struck is adapted to so expand as to substantially completely fill the socket 5 and thus effectively anchor an extremity of the key 10 75 to the nut or bur 3. The key 10 has slidably mounted thereon a second clench or head 12 adapted to be inserted within an aligned socket 8 in the nut or bur 4 and adapted to be suitably expanded in order to effectively 80 tie or connect the burs or nuts 3 and 4, in a manner which is believed to be self-evident, and whereby said nuts or burs are effectively locked against relative movement.

In practice, the nut or bur 4 is adapted to 85 be suitably adjusted in order to assure the requisite alinement of the sockets 5 and 8 and when such adjustment results in a separation of the nuts or burs 3 and 4, a washer 14 is adapted to be positioned within such 90 space in order that the requisite co-action 95 may be had between the nuts or burs 3 and 4, it being readily observed that the initial purpose of the nut or bur 4 is to hold the nut or bur 3 against retrograde or outward 100 movement relative to the bolt B. It will also be readily apparent that by having the head or clench 12 slidably mounted upon the key 10, the requisite application of the key 105 may be effected with convenience and facility, irrespective of any possible separation of the nuts or burs 3 and 4.

From the foregoing description, it is thought to be obvious that a nut lock constructed in accordance with my invention 110 is of an extremely simple and comparatively inexpensive nature and is particularly well

adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

In combination with a bolt provided with reversely directed threads, a nut engageable 15 with each threaded portion of the bolt, said

nuts having sockets in their side faces adapted to aline, a key, and expansible heads carried by said key adapted to be inserted within the alined sockets of the nuts, the side walls of said nuts being concaved, said nuts 20 being also provided in their side faces with open-ended slots in communication with the sockets and adapted to aline and through which the key is adapted to extend.

In testimony whereof I hereunto affix my 25 signature in the presence of two witnesses.

DOMENICO T. CASALE.
